CLAIM

The ornamental design for a test board for wire corrosion testing, as shown and described.

DESCRIPTION

FIG. 1 is a view in elevation of an obverse of a test board for wire corrosion testing hereof.

FIG. 2 is a view in elevation of the reverse of the test board of FIG. 1.

FIG. 3 is a view in elevation of a first side of the test board of FIG. 1, with the second, opposite side of which being a mirror image thereof.

FIG. 4 is a top view of the test board of FIG. 1, enlarged for presentation purposes.

FIG. 5 is a bottom view of the test board of FIG. 1, enlarged to correspond with FIG. 4.

FIG. 6 is a top perspective view of the test board of FIG. 1. FIG. 7 is a view in elevation of the test board of FIG. 1, to which separate electrical test wires, shown in dashed lines and not forming a part of the present invention, are mounted for immersion in separate liquid and vapor states of a test substance and passing electrical current therethrough for wire corrosion testing; and,

FIG. 8 is a perspective, exploded view including the test board of FIG. 1, to which separate electrical test wires, shown in dashed lines and not forming a part of the present invention, are mounted, in general as in FIG. 7, for immersing in separate liquid and vapor states of a test substance in an included test vessel of a modular test unit, and having electrical current passed through the test wires for monitoring and analysis with respect to corrosion testing of the test wires immersed in the test substance, the test vessel and modular test unit shown in dashed lines and not forming a part of the present invention.
